UNITED STATES PATENT OFFICE

1,988,011

EAR PROTECTOR

Mordicha Margolish, Hawthorne, Calif.

Application, July 29, 1932, Serial No. 625,641

4 Claims. (Cl. 128—151)

This invention relates to a device for protecting the ears and relates more particularly to a device for preventing the entrance of water, etc., into the ears. It is a general object of the invention to provide a practical, sanitary and effective device for protecting the ears during shampooing of the head and treatment of the hair.

When shampooing the head and treating the hair, water or other liquid often enters the ears, which is extremely uncomfortable, and in some instances, injurious.

An object of the present invention is to provide a device for preventing the entrance of water, etc., into the ears during the shampooing of the head or treatment of the hair, that is convenient to handle and easy to apply.

It is another object of the invention to provide an ear protecting device of the character mentioned that is comfortable when in position on the ears, and that gives a pleasant sense of security against the passage of water, etc., into the ears.

It is another object of the invention to provide an ear protecting device of the character mentioned that does not materially interfere with the hearing when in its protective position on the ears.

It is another object of the invention to provide an ear protector of the character mentioned that includes replaceable or renewable sanitary shields that prevent direct contact of any of the parts of the device with the ears or head of the user or wearer.

It is another object of the invention to provide sanitary shields for use on an ear protecting device of the character mentioned that are formed so that they may be easily and quickly applied to and detached from the ear inclosing elements of the device.

It is another object of the invention to provide an ear protecting device of the character mentioned that is compact and light in weight and that is simple and inexpensive of manufacture.

A further object of the invention is to provide a device for protecting the ears in which the ear covering elements are automatically held in their proper position on the ears by means of the band or strap that connects them.

Further objects and features of the invention will be best and more fully understood from the following detailed description of a typical form and application of the invention, throughout which description reference is had to the accompanying drawing, in which:

Fig. 1 is a view illustrating the device provided by the invention in position on the ears of a wearer. Fig. 2 is a top or plan view of the device. Fig. 3 is an enlarged side elevation of one of the ear inclosing and protecting units showing the sanitary shield in position on the unit. Fig. 4 is a view similar to Fig. 3, being a view of the inner side of the unit with the sanitary shield removed. Fig. 5 is an enlarged transverse detailed sectional view taken as indicated by line 5—5 on Fig. 3. Fig. 6 is a side elevation of the sanitary shield for use in the ear protecting unit, and Fig. 7 is a vertical detailed sectional view taken as indicated by line 7—7 on Fig. 6.

The ear protecting device provided by the invention includes generally, two ear protecting units A, each including a body 10 and a yielding member 11 on the body for sealing about the ear, replaceable sanitary shields 12 for the units A, and a strap or band 13 connecting the units A and operable to yieldingly hold the units in their proper positions on the ears.

The ear protecting units A are alike or identical in construction and design, one being intended for the right ear and the other for the left ear. As the units A are alike, I will proceed with a description of one unit, it being understood that the description may apply equally well to both the units A.

The body 10 of the unit A is a flat plate-like member for extending over the major portion of the ear and for carrying the sealing member 11. The body 10 may be comparatively rigid or unyielding and may be formed of metal or other suitable material. In the event that the body is formed of metal, it is preferred to plate it or otherwise treat it to resist rust or corrosion. In accordance with the invention, the body 10 is shaped to conform generally to the outline of the human ear, that is, the outline of the body 10 corresponds generally to the outline of the helix and lobe of the average human ear.

The upper and outer edge 14 of the body 10 is rounded or curved to correspond to the curvature of the edge of the helix of the ear, while the lower edge 15 of the body is rounded to correspond generally to the lobe of the ear. The inner edge 16 of the body 10 which occurs adjacent the line of joinder of the forward portion of the ear with the head, when the unit is in position on the ear, may be substantially straight as illustrated throughout the drawing. In accordance with the invention, an opening 17 is provided in the body to permit sound to reach the ear. Means is provided in connection with the body 10 to prevent water or

other liquid from passing through the sound opening 17. A louver 18 is provided on the outer side of the body 10 to exclude water from the opening 17. In the particular construction illustrated in the drawing, the sound opening 17 is substantially semi-circular, and the louver 18 is formed of the material that has been pressed outwardly from the body to provide the opening 17. It will be apparent how the opening 17 and the louver 18 may be formed by making a straight cut in the flat body 10 and bending the material outwardly from one edge of the cut to form the rounded louver 18.

During the shampooing of a woman's head and treatment of her hair, the head is held with the face up as illustrated in Fig. 1 of the drawing, while a man's head is usually face downward when his head is being shampooed etc. When the ear protecting device is intended to be used on women, the louver 18 extends downwardly as illustrated throughout the drawing to prevent the downwardly flowing water from passing through the opening. When the ear protector is intended to be used on men, the louver extends across or over the opening 17 toward the flat inner edge 16 of the body so that it effectively sheds the water when the head is positioned with the face down.

The sealing member 11 is a yielding or resilient element provided on the body 10 to insure a proper seal between the body 10 and the head and ear of the user to prevent the leakage of water into the ear. Further, the member 11 operates to properly center and hold the unit A on the ear. In the preferred form of the invention, the sealing member 11 is integral and is formed of rubber, or the like. It is preferred to construct the member 11 of a good grade of gum rubber so as to be pliable and soft. In accordance with the invention, the sealing member 11 is carried on the edge portions of the body 10 and extends completely around the body. A groove 19 is provided in the inner edge of the member 11 to receive the edge portions of the body 10. The groove 19 is proportioned so that the member 11 tightly grips the body 10 when the member is in its position on the body.

The sealing member 11 in being flexible, may be easily and quickly sprung on to the body 10 so that the edge portions of the body are received in the groove 19. Due to the construction of the member 11 and its manner of connection with the body 10, it may be readily replaced when desired or necessary and may be removed for cleansing etc. It is to be understood that the sealing member 11 has a tight sealing fit with the body 10.

A lip or flange 20 is provided on the inner side of the sealing member 11 to engage over the upper and outer edge portions of the helix of the ear. The flange 20 is integral with the member 11 and is shaped to effectively engage over and partially around the upper and rear edge portions of the ear. In the preferred construction, the flange 21 extends along the entire upper edge portion of the member 11 and substantially the entire outer edge portion of the member as clearly illustrated in Fig. 4 of the drawing. The opposite ends of the flange 20 gradually taper away to join the main or principal part of the sealing member 11. The flange 20 is intended to engage over the upper and rear edge portions of the ear and projects inwardly at an angle to the flat surface of the body 10 so as to be effective in its engagement with the ear. It will be apparent how the flange 20 operates to properly position the unit A on the ear and to positively prevent the leakage of water into the ear.

The units A may be employed or used so that the yielding sealing member 11 directly engages the ears and head. However, the invention provides renewable or replaceable sanitary shields 12 adapted to be applied to the units A to prevent direct contact of any parts of the units with the ears and head of the user.

The shields 12 are simple and inexpensive, and may be easily and quickly applied to and removed from the ear protecting units A. Each shield 12 is a single piece of paper or other suitable material and is shaped so as to effectively cover the entire inner side of a unit A. The shape of the shield 12 corresponds generally to the shape of the ear protecting unit A. In accordance with the preferred embodiment of the invention, the shield 12 is folded, shaped or pressed to have a fold 25 along its upper and outer edge adapted to extend under the flange 20, and a rim or lip 26 to cover the outer side of the flange 20. The fold 25 fits under the flange 20 in a manner to hold the flat major portion 27 of the shield in position where it extends across the inner side of the unit A, while the lip 26 is shaped to effectively conform to the configuration of the flange 20 and to completely cover the outer side of the flange. The manner in which the shield 12 fits on the unit A is clearly illustrated in Fig. 5 of the drawing. The main portion 27 of the shield 12 is preferably sufficiently large to project outwardly from the edges of the unit A. A sound opening 30^a is provided in the flat major portion 27 of the shield to register with the opening 17 in the body 10. The opening 30^a is preferably somewhat larger than the opening 17 so as to insure its proper registration with the opening 17. It will be apparent how the shield may be easily and quickly applied to the unit and how it positively prevents direct contact between any part of the unit and the ear or head.

The strap or band 13 connects the two units A and is adapted to yieldingly hold them in position on the ears. The strap or band 13 may be formed of metal, such as spring steel or the like, and may be suitably plated or polished. In the embodiment of the invention illustrated in the drawing, the strap or band 13 is substantially U-shaped, being shaped to extend under the chin when the device is in use. The units A are pivotally connected to the opposite end portions of the strap or band 13. In the particular case illustrated in the drawing, the units A are pivotally connected with the ends of the strap or band 13 by suitable pins or rivets 28. The pivotal connections of the units A with the strap or band 13 is such that the units are free to tilt to a limited extent so that they may properly engage over the ears. It is a feature of the invention that the strap or band 13 is shaped so that it does not come into contact with the face of the user of the device. The band 13 is bent outwardly adjacent the units A as at 29 in the drawing, and has straight parallel portions 30 which are maintained spaced from the cheek of the wearer by the bent parts 29. The central portion 31 of the strap or band 13 is rounded or curved to fit under the chin of the user with suitable clearance.

It is believed that the utility and practicability of the ear protector provided by the invention will be readily apparent from the foregoing de-

tailed description. The strap or band 13 is such that it may be easily sprung to allow for the ready and easy application of the units A to the ear. The loose pivotal connections of the units 5 A with the strap or band 13 permit the units A to be properly arranged on the ears and allows the strap or band 13 to be swung to a free or comfortable position. The sanitary shields 12 may be easily applied to the units A prior to 10 their positioning on the ears and positively prevent direct contact of any of the parts of the units with the ears or head. The openings 30^a in the shields 12 register with the openings 17 in the bodies 10 so that the hearing is not materially 15 interfered with when the units are in position over the ears. When applying the units A to the ears, the flanges 20 engage over the upper and outer edge portions of the ears and thus partially support the units in their proper position 20 on the ears. The resilient strap or band 13 yieldingly urges the units A inwardly against the ears so that effective seals are provided about the ears. The yielding sealing members 11 are shaped and formed so as to be particularly 25 effective in sealing about the ears and so as to be very comfortable. When it is desired to detach the device the sides of the strap or band 13 may be bowed or sprung outward to permit the disengagement of the units A from the ears. It 30 is to be noted that the invention provides a simple, effective device for protecting the ears and for preventing the entrance of water into the ears. The provision of the sanitary shields 12 particularly adapts the device for use in beauty 35 shops, barber shops, etc. The device may be easily and quickly applied, and is comfortable when in position on the ears.

Having described only a typical preferred form and application of my invention, I do not 40 wish to limit myself to the specific details set forth, but wish to reserve to myself any changes or variations that may appear to those skilled in the art or fall within the scope of the following claims.

45 Having described my invention, I claim:

1. An ear protector of the character described comprising an ear enclosing unit including a body having an opening to allow sound to reach the ear, a louver on the body to exclude liquid from the opening, means on the body for sealing about the ear to exclude liquid therefrom, and a sanitary shield removably carried on the inner side of the unit to prevent direct contact of the body and said means with the wearer, there being an opening in the shield to register with 10 the opening in the body. 5

2. In a device of the character described an ear protecting unit including a body having an opening to allow sound to reach the ear, and a yielding member on the body for sealing with 15 the head adjacent the ear and having a flange for engaging over the edge portions of the helix of the ear, and a sanitary shield for the unit to prevent direct contact of said member with the head or ears, the shield having a fold to engage 20 under the flange of the member, there being an opening in the shield registering with the opening in the body. 25

3. In a device of the character described an ear protecting unit including a body, and a yielding member on the body for sealing with 30 the head adjacent the ear and having a flange for engaging over the edge portions of the helix of the ear, and a sanitary shield for the unit to prevent direct contact of said member with the head or ears, the shield having a fold to engage 35 under the flange of the member and a lip to engage over the flange, the fold and lip removably holding the shield on the unit. 40

4. A sanitary shield for use on an ear protector having a yielding sealing member for sealing with the head and ear, there being a flange on the member for engaging over the edge of the ear said shield including a main part to extend over the inner side of the protector, a fold in the 45 main part to extend under said flange, and a lip along an edge of the fold for engaging over the flange, the fold and lip removably holding the shield on the protector. 45

MORDICHA MARGOLITH. 45
